Inventor

Yours truly,

Attorney

UNITED STATES PATENT OFFICE

EDGAR D. MOORE, OF MANSFIELD, OHIO, ASSIGNOR TO THE OHIO BRASS COMPANY, OF MANSFIELD, OHIO, A CORPORATION OF NEW JERSEY

TROLLEY-POLE BASE

Application filed September 16, 1929. Serial No. 392,767.

My invention relates to improvements in connection with trolley poles and bases therefor.

The object of my invention is to perfect the contact relation between the trolley pole and the trolley base as current must flow from the trolley pole to the base and thence to the apparatus upon a car and therefore all joints in connection should be as efficient as possible.

The trolley base and pole are mounted upon the roof of the car and are exposed to all kinds of weather and are formed, as a rule, of iron which is subject to corrosion and very often it is necessary to change trolley poles on a run and this is usually done by the car crew who are more or less rushed and take very little care or precaution to see that the contacting parts are free of rust or corrosion.

I have provided means for practically eliminating the question of corrosion, or at least have reduced it to a very small amount as compared with that to be found on poles and bases today. Further, the contact between non-ferrous metals such as copper is much better than that between two pieces of ferrous metal.

My invention resides in the new and novel construction, combination and relation of the various parts and in the various steps used in the process described in the specification and shown in the drawing.

In the drawing:—
35 Fig. 1 is a side view in elevation of a trolley base and pole with my improvement incorporated therein.

Fig. 2 is a face view of one of the clamping members as shown in Fig. 1.

40 Fig. 3 is an end view of Fig. 2.

Fig. 4 is a sectional view on the line 4—4 of Fig. 1.

Fig. 5 is a trolley pole having incorporated therewith my advance in the art.

45 Fig. 6 illustrates the method of applying my invention to the end of a trolley pole.

In the preferred embodiment of my invention I employ a trolley base provided with a stationary base member 1, a turret member 2 mounted upon the base to rotate about the

vertical axis α — α . Pivots mounted to the turret is an arm 3 movable in a vertical plane about its pivotal point 4 and biased to have its free end moved upwardly by means of the spring or springs 5 secured to the arm 55 and turret.

The arm 3 is usually provided with a groove 6 shown in Fig. 4 in which the trolley pole 7 is positioned and the pole is held in position by means of the clamping members 60 8 secured to the arm by means of the bolts and nuts 9.

Interposed between the arm 3 and the pole 7 is a coating 10 which is applied to the pole 7 at the end thereof and adheres to the surface of the pole, forming a fixed relation therewith, as is the case with an alloyed union or what might be termed a sprayed union, as when a coating of metal is sprayed upon another metal surface.

The surface of the clamps 8 which contact with the pole may also be provided with a coating 11 and likewise the surface of the groove 6 may be provided with a coating 12. It is quite evident that the coating might 75 rest upon the pole and either or both parts 3 and 8 and also it is evident that the coatings 10 shown in Fig. 1 may be made continuous as shown by the coating 13 in Fig. 5.

The coating may consist of various non-ferrous metals, the conductivity and non-corrosive properties being much greater than those of iron. The non-ferrous coating may consist of zinc or a brazing spelter such as an alloy of copper and zinc, or it may consist of 80 pure copper. Also other metals may be used of a non-corrosive character in the coating, such as Monel, chromium and stainless steel, but these latter metals have a low conductivity and therefore do not meet one requirement, namely conductivity.

The zinc coating may be applied, as is the common practice, with galvanizing or tin may be substituted for the zinc and such coating would have what might be termed 85 an alloyed union with the base metal if the coating is properly applied, but such coating would have at least a very tenacious hold upon the base metal. The brazing spelter might be applied to the parts in a manner 90

similar to that of applying the zinc coating. The copper, however, could be very readily and cheaply applied by means of the metal spray process, which consists in melting a small copper wire in a gas or arc flame and projecting the molten metal in very fine particles forcibly against the surface of the parts to be coated. Such a coating is very fine grained, uniform and forms a stronger adhering union with the parts upon which it is sprayed. The non-corrosive metals, Monel and stainless steel, may also be applied by the metal spray process but the chromium would probably be applied by the electro-plating process.

While I have referred to zinc, brazing spelter, copper and tin as non-corroding metals, I do not use this term as absolute because such metals will corrode or oxidize slightly but such corrosion consists of a very thin and delicate film as an oxide, which is very easily broken through when two parts are brought into strong contact.

In Fig. 6 I have indicated a method of spraying the metal coating upon the end of a trolley pole and show at 14 a spray gun which is used to considerable extent at the present day and is so arranged as to fuse a metal wire 15 and to finally divide and project the same at high velocity upon the end of the pole 16. One form of apparatus for carrying out the process is shown and described in Patent 1,100,602. This apparatus can also be used in spraying onto the surface of the parts zinc, brass, bronze, cadmium or other metals as may be desired.

In Fig. 5 I have shown both ends of the pole provided with a coating and the use of the coating 13 has already been explained, and the coating 17 forms an improved surface for the attachment of the current collector thereto as current must pass from the collector to the pole and from the pole to the trolley base.

It will be recognized that my improvement may be applied to various parts of a trolley base, in varying degrees and in the form of various metals, and therefore I wish to be limited only by my claims.

50 I claim:—

1. A trolley device comprising a stationary base member, a rotatable turret thereon, a pivotally mounted arm on the turret, springs biased to move the arm about its pivot, a trolley pole secured to the arm, means to secure the pole to the arm and a coating of non-ferrous metal on the arm and contacting with the pole.

60 2. A trolley device comprising a stationary base member, a rotatable turret thereon, a pivotally mounted arm on the turret, springs biased to move the arm about its pivot, a trolley pole secured to the arm, means to secure the pole to the arm and a coating of non-

ferrous metal on the arm and securing means and contacting with the pole.

3. A trolley device comprising a stationary base member, a rotatable turret thereon, a pivotally mounted arm on the turret, springs 70 biased to move the arm about its pivot, a trolley pole secured to the arm, means to secure the pole to the arm and a coating of non-ferrous metal on the arm.

4. A trolley device comprising a stationary 75 base member, a rotatable turret thereon, a pivotally mounted arm on the turret, springs biased to move the arm about its pivot, a trolley pole secured to the arm, means to secure the pole to the arm and a coating of 80 non-ferrous metal on the pole and contacting with the arm.

5. A trolley base and a trolley pole of ferrous metal secured together and a coating of copper interposed between the pole and base 85 and secured to one of the said parts.

6. A trolley base having a ferrous arm pivotally mounted to move in a vertical plane and adapted to receive a trolley pole and a sprayed coating of non-ferrous metal on the 90 arm positioned to contact with the pole.

7. A trolley base having a ferrous arm and adapted to receive a trolley pole and an adhering sprayed coating of substantially non-corroding metal on the arm positioned to 95 contact with the pole.

8. A trolley base and a trolley pole of ferrous metal secured together and a sprayed coating of copper base metal interposed between the pole and base and secured to one 100 of the parts.

9. A trolley base and trolley pole both of ferrous metal and sprayed metallic coatings of non-ferrous metal secured to the base and to the pole and contacting with each other. 105

10. A trolley base and trolley pole both of ferrous metal and electrically conducting metallic coatings of non-ferrous metal secured to the base and to the pole and contacting with each other.

11. A clamp member for a trolley pole comprising a ferrous body member having a grooved portion and an adhering coating of copper alloy metal lining the groove to increase the conductivity between the clamp 115 and pole.

12. A clamp member comprising a ferrous body member having a grooved portion and a sprayed coating of non-ferrous metal adhering to the body member.

13. A trolley pole of ferrous metal having the outer surface for a distance back from one end provided with a layer of deposited non-ferrous metal in direct and adhering contact with the said surface to form a conducting coating.

14. A tubular trolley pole of ferrous metal having one of its surfaces for a distance back from one end provided with a conducting, metallic layer of non-ferrous metal comprising 130

ing a plurality of particles of the non-ferrous metal contacting with and adhering directly to the said surface to form a conducting coating.

5 15. A trolley pole of ferrous metal having an adhering coating at one end of sprayed non-ferrous metal.

16. A trolley pole of ferrous metal having an adhering coating of copper adapted
10 to contact with parts secured thereto.

In testimony whereof I affix my signature.
EDGAR D. MOORE.
